INSOLE

Michele Cuozzo, Lynn, Mass., assignor to United
Shoe Machinery Corporation, Flemington,
N. J., a corporation of New Jersey

Application December 2, 1940, Serial No. 368,199

10 Claims.

(Cl. 36—22)

This invention relates to insoles and particularly to insoles for use in the manufacture of welted shoes.

Insoles for welt work are usually prepared by the making of an inside channel and an outside channel and turning the channel flaps up against each other to form a sewing rib. Sometimes an outside channel flap alone is used to form the sewing rib. In order to provide in this manner a rib of adequate strength it is necessary to employ leather of good quality and frequently even the better grades of insoles are reinforced with a layer of canvas covering the body of the insole and extending up the inside of the rib to the top thereof.

Objects of this invention are to provide an insole having a rib of great flexibility and adequate strength which will be firmly anchored to the body of the insole and in which the channeling and reinforcing operations are omitted or reduced to a minimum.

The illustrated insoles, which embody my invention, are each provided with a series of loops of strong thread positioned and arranged to reinforce a sewing rib. The insole may be channeled to provide either an inside or an outside channel flap and the series of loops formed through the body of the insole adjacent to the channel flap, the loops being preferably secured (for example, by cement) to the channel flap to form a strong sewing rib firmly anchored to the body of the insole.

In another form of the invention, the insole is channeled to provide both an inside and an outside channel flap and the series of thread loops is anchored in the between-substance along a line between the channel flaps which are preferably cemented to the series of thread loops, a very strong connection between the sewing rib and the body of the insole being thus established. For some purposes an unchanneled insole may be provided, along the line where the usual sewing rib is located, with a series of thread loops formed by passing loops of thread through the body of the insole, the thread loops being preferably reinforced, at least on the inner side, with a strip of canvas one marginal portion of which is secured to the body of the insole and the other marginal portion secured against the inner face of the series of thread loops. This construction avoids any channeling operation and the strip of canvas provides a continuous surface on the inside of the sewing rib so that no obstruction is offered to the passage of the channel

guide of the inseam sewing machine along the inner face of the rib.

In the drawing,

Fig. 1 is a perspective view of an insole provided with an inside channel the lip of which on its outer side is reinforced with a series of thread loops passing through the body of the insole;

Fig. 2 is a fragmentary view in perspective and in section illustrating a form of insole having an outside channel flap on one side and a similar flap on the other side, loops of thread being anchored in the body of the insole between the flaps to reinforce the outer side of the outside flap and having their anchorage to the body of the insole concealed by the other flap;

Fig. 3 is a fragmentary view in perspective and in section illustrating an insole having an outside channel the flap of which is reinforced by loops of thread passing through the body of the insole, the portions of the thread which appear on the inner face of the insole being concealed by a cover;

Fig. 4 is a fragmentary view in perspective and in section illustrating a form of insole which is unchanneled and in which loops of thread are passed through the entire thickness thereof, the series of loops being covered on the inside by a fabric strip secured to the body of the insole and to the inner face of the series of loops;

Fig. 5 is a fragmentary view in perspective and section illustrating an insole having both an inside and an outside channel and having loops of thread passed through the between-substance so that a series of loops lies between the two channels the flaps of which are secured to it; and

Fig. 6 is a fragmentary sectional view of a welted shoe made by utilizing an insole of the type illustrated in Fig. 5.

In Fig. 1 of the drawing, the numeral 10 indicates an insole having an inside channel 12 the lip 14 of which is turned up. Along the base of the lip 14 on its outer side a series of thread loops 16 is formed by passing loops of a continuous thread through the insole from its inner side to its outer side, the loops lying in close proximity to the outer face of the inner lip 14. The series of thread loops may be formed by hand, by the use of a fairstitch machine such as that disclosed in Letters Patent of the United States No. 563,871, granted July 14, 1896, on application of Edward F. Mower, or by the use of a lockstitch machine such as that disclosed in Letters Patent of the United States No. 473,870, granted April 26, 1892, on application of French and Meyer. In the use of the latter machine the

tension on one of the threads, that is, the thread 16, will be loosened and that on the other thread, such as 18, tightened so that the series of loops will be formed in the thread 16, and the thread 18 will merely pass directly from loop to loop. By pulling on the ends of the thread 18 the whole series of loops in the thread 16 may be drawn inwardly against the flap 14. Preferably the outer face of the channel lip 14 and the series of loops will be united by a suitable cement into a substantially unitary sewing rib.

In Fig. 2 is illustrated an insole 20 provided with an outside channel flap 22 reinforced by a series of loops 16. In this instance the insole body 20 has been split in from its edge to form three flaps or portions 22, 24, 26, the loops of the thread 16 being inserted through the portion 24 and the anchorage of the thread loops covered by the flap 26. Thus an insole having a rib is provided the inner face of the rib of which is perfectly smooth and the outer face of which has a discontinuous reinforcement.

In Fig. 3 an insole body 30 is provided with an outside channel the flap 32 of which is upturned. Then, through the feather portion 34 of the insole, loops of thread 16 are inserted, a series of loops lying just outside the erect flap 32. Thus the insole is provided with a lip one part 32 of which is continuous and the other part composed of the loops 16 is discontinuous. To provide a smooth surface on the inner face of the insole a covering layer 38 of suitable material may be applied to that face and preferably is carried around the edges of the feather portion 34, as indicated in Fig. 3.

Fig. 4 illustrates another construction which provides an insole having a rib one part of which is continuous and the other part discontinuous. In this case the thread loops 16, as disclosed in Figs. 1 and 2, are passed through an insole body 40 and the series of loops is reinforced on its inner side with a strip of canvas 42 one marginal portion of which is secured to the body of the insole 40 and the other marginal portion of which is laid against the inner face of the series of loops and preferably secured thereto, for example by cement. If desired, of course, a cover like that shown at 38 in Fig. 3 may be used. If desired, a thread like that shown at 18 in Fig. 1 may pass through the loops 16.

Still another construction in which an insole rib is provided part of which is continuous and part discontinuous is illustrated in Fig. 5. In this case an insole body 50 is provided with an outside channel flap 52 and an inside channel flap 54, as is usual in the manufacture of welt insoles. Then, to reinforce and strengthen the rib formed by the flaps 52, 54, a line of loops 16 similar to those shown in Fig. 3 is inserted through the between-substance of the insole so that the series of loops lies between the two flaps, and the loops and the flaps may be secured to each other by cement. In this construction the composite rib is firmly anchored to the insole by the thread which passes from loop to loop on the inner side of the insole. In case this thread, which has the appearance of stitches on the inside of the insole, is objectionable, a cover like that shown at 38 in Fig. 3 may be provided.

In use, any of the above-described insoles will be attached to a last 60 (Fig. 6) and upper materials 62 will be lasted over the marginal portion or feather of the insole against the outside of the rib. The upper 62 and a welt 64 will then be attached by stitches 66 to the rib, the stitches pass-

ing through the continuous portion of the rib and embracing one or more of the strands of thread forming the loops 16 which constitute a discontinuous reinforcement for the lip. It will be apparent that the thread loops, either alone or in connection with a continuous member formed integral with the insole or attached thereto, will afford a very strong and dependable anchorage for the stitches 66 even when, as is usual, the top portion of the rib, including the bights of the loops and the strand of thread 18, if present, are trimmed off flush with the sole-engaging face of the welt 64. In completing the shoe, a filler 68 will be applied to the shoe bottom, and a sole 70 laid thereon and attached to the welt 64, for example, by stitches 72.

Having thus described my invention, what I claim as new and desire to secure by Letters Patent of the United States is:

1. An insole for use in the manufacture of welted shoes comprising a body portion, a continuous upstanding flap on the body portion, and a series of thread loops anchored in the body portion and arranged to lie against the outer face only of the continuous flap to form with the flap a sewing rib.

2. An insole for use in the manufacture of welted shoes comprising a body portion, a series of thread loops anchored in the body portion, said loops being located to form a discontinuous sewing rib at a suitable distance from the edge of the insole, and a continuous backing for the discontinuous rib, said backing being independently connected to the body of the insole and engaging the inner face of the discontinuous rib.

3. An insole for use in the manufacture of welted shoes comprising a body portion, a series of thread loops formed by passing loops of continuous thread through the body portion, said loops being located to form a discontinuous sewing rib at a suitable distance from the edge of the insole, and a continuous backing flap for the discontinuous rib, said backing flap being connected independently of said loops to the inner face of the discontinuous rib and to the body of the insole.

4. An insole for use in the manufacture of welted shoes comprising a body portion, a series of threads anchored in the body portion, and a flap integral with the body portion to the outer face of which the threads are secured, the height-wise extent of the threads corresponding to the width of the integral flap.

5. An insole for use in the manufacture of welted shoes comprising a body portion, an integral flap formed by channeling the body portion, and a series of thread loops anchored in the body portion and arranged adjacent to the outer face of the flap and being of sufficient height to form with the flap a sewing rib.

6. An insole for use in the manufacture of welted shoes comprising a body portion, an integral flap formed by channeling the body portion, a series of thread loops anchored in the body portion and arranged against the outer face of the flap, the loops extending to the top of the flap to form with the flap a sewing rib, and means for concealing the anchorage of the loops in the body portion.

7. An insole for use in the manufacture of welted shoes comprising a body portion, a series of thread loops formed by passing loops of a single continuous thread through the body portion, said loops upstanding from the body portion being located to form a discontinuous sewing rib

at a suitable distance from the edge of the insole, and a continuous thread passing through the loops, said last-named thread being tensioned to incline the loops inwardly.

8. An insole for use in the manufacture of welted shoes comprising a body portion, a series of thread loops formed by passing loops of continuous thread through the body portion, said loops being located to form a discontinuous sewing rib at a suitable distance from the edge of the insole, and a continuous fabric backing strip for the discontinuous rib, one marginal portion of said backing strip being secured to the inner face of the discontinuous rib and the other marginal portion of said backing strip being secured to the body of the insole independently of the loops.

9. An insole for use in the manufacture of

welted shoes comprising a body portion, said body portion being channeled to form inner and outer channel flaps, and a series of thread strands anchored in the between-substance of the insole between the channel flaps, extending to the top of the flaps and adapted to be embraced by the flaps to form a thread-reinforced sewing rib.

10. An insole for use in the manufacture of welted shoes comprising a body portion, said body portion being channeled to form inner and outer channel flaps, and a series of thread strands anchored in the between-substance of the insole between the channel flaps, said strands extending heightwise of the flaps to reinforce them throughout their extent, said flaps being cemented to the thread strands to form a thread-reinforced sewing rib.
